(57) **CLAIM**

The ornamental design for the assembly of pants with integrated removable waistpack, as shown and described.

DESCRIPTION

FIG. 1 shows a front, right-side perspective view of the pants with integrated removable waistpack.

FIG. 2 shows a front view of the assembly of FIG. 1.

FIG. 3 shows a left-side view of the assembly of FIG. 1.

FIG. 4 shows a back view of the assembly of FIG. 1.

FIG. 5 shows a right-side view of the assembly of FIG. 1.

FIG. 6 shows a top view of the assembly of FIG. 1.

FIG. 7 shows a bottom view of the assembly of FIG. 1.

FIG. 8 shows a front, right-side perspective view of the pants with integrated removable waistpack with the waistpack removed from the assembly for clarity of disclosure.

FIG. 9 shows a front view of the pants of FIG. 8.

FIG. 10 shows a left-side view of the pants of FIG. 8.

FIG. 11 shows a back view of the pants of FIG. 8.

FIG. 12 shows a right-side view of the pants of FIG. 8.

FIG. 13 shows a top view of the pants of FIG. 8.

FIG. 14 shows a bottom view of the pants of FIG. 8.

FIG. 15 shows a left-side perspective view of the pants with integrated removable waistpack with the waistpack only shown removed from the assembly for clarity of disclosure; and,

FIG. 16 shows a front view of the waistpack from FIG. 15. The broken lines form no part of the claimed design and illustrate an environment for the portion illustrated with solid lines. The lower leg, interior and buckle regions of the pants with integrated removable waistpack, shown in broken lines, are not part of the claimed design.

1 Claim, 9 Drawing Sheets
